ADJUSTABLE LIGHT SOURCE FOR PHOTOGRAPHIC PRINTING MACHINES

Filed Oct. 22, 1929

UNITED STATES PATENT OFFICE

ROY S. HOPKINS, OF ROCHESTER, NEW YORK, ASSIGNOR TO EASTMAN KODAK COMPANY, OF ROCHESTER, NEW YORK, A CORPORATION OF NEW YORK

ADJUSTABLE LIGHT SOURCE FOR PHOTOGRAPHIC PRINTING MACHINES

Application filed October 22, 1929. Serial No. 401,407.

This invention relates to photography, and more particularly to a source of light for photographic printing machines.

It has for its object to provide a source of light from which light rays of different known intensities may be obtained with minimum effort on the part of an operator. Another object is to provide a source of light having a plurality of light intensities which may be used one at a time. Another object of my invention is to provide a multiple light source which is adjustable to bring a single source of light into operative position at a time and to permit other sources of light of different intensities to be operatively positioned for printing. Another object of my invention is to provide a source of light including a movable base having a plurality of lamp receptacles arranged to accurately position the filaments of each lamp in a printing position. Still another object is to provide a pivoted base having a plurality of lamp sockets, each socket being adapted to make a circuit when swung into an operative printing position. Still another object is to provide a source of light having a plurality of sockets movably mounted and means for automatically making a circuit through any one socket positioned for printing.

Other objects will appear from the following specification, the novel features being pointed out in the claims at the end thereof.

Coming now to the drawings, wherein like reference characters denote like parts throughout:

Fig. 1 is a diagrammatic side elevation of a printer having a portion of its side broken away, showing in elevation, a detail of my invention.

Fig. 2 is a front elevation of the lamp bracket supporting a plurality of lamp sockets.

Fig. 3 is a front elevation of the contact block.

Fig. 4 is a detail in section of a spring contact and the contact block.

Fig. 5 is a diagram of a plurality of electric circuits employed by my invention.

Fig. 6 is an elevation partly in section of a

modification of a lamp bracket supporting a series of lamp sockets, illustrating another embodiment of my invention.

My present invention is particularly adapted for use in a printing machine of the type shown in my copending application, Serial No. 153,882, filed December 10, 1926 although obviously it may be used with other type of machines. For the operation of the printer parts, reference may be had to the showing in my copending application.

As shown in Fig. 1, a printer 1, is provided with a source of light comprising a plurality of lamps 2, which are supported by a bracket 3. The bracket 3 also supports a block 4 which carries a plurality of contact points with which the spring contact 6 completes a circuit. The spring contact 6 is supported by an insulated block 7, which is mounted with bracket 3 on the bolt 8, said bolt acting as a pivot for the bracket. A reflector 9 is provided to direct the light rays through the aperture 10 to the mirror 11 which directs said light rays to the printing panel of the printer 1, as fully described in my copending application above referred to.

The bracket 3 as best shown in Fig. 2, comprises a base 12, pivoted on the bolt 8, and a plurality of lamp sockets for lamps of different intensities. For example one socket 14 may be provided for a 1000 watt lamp, and the other two sockets 15 and 16 may contain 250 and 100 watt lamps. The base 12 also supports a contact block 4 carrying a plurality of contact buttons 18 one connected to each lamp socket as by wires 19, with wires 20 leading to a source of power 21, as shown in Fig. 5.

The contact button 18 and the contact point 22 of spring contact 6 may be of any desired form, but the nipple and dimple types as shown in Fig. 3 and Fig. 4 are preferred. When contact point 22 enters a dimple 18 it both makes a circuit and acts as a snap-latch for holding bracket 3 in a set position.

A modification of bracket 3 is shown in Fig. 6, comprising a base 23, pivotally mounted at 17, supporting a plurality of lamp sockets 24, said lamp sockets being adjustably mounted as by thumb screw 25, said adjustment, pro-

viding means for raising or lowering the lamps to bring the concentrated lamp filaments opposite the aperture 10. Apertures 26 are provided for the admission of electric wires.

5 When an operator is making prints from a plurality of negatives, he is frequently required to change the strength of light in the printing machine due to the density of the individual negatives. To do this, by the present method, he must reduce the current to the lamp by a rheostat, which method has a number of disadvantages. First, the range of light intensities can not always be taken 10 care of by a rheostat. Second, a change in the rheostat does not produce an instantaneous change in lamp brilliance. Third, a color change in the illumination takes place in altering lamp intensities through a wide 15 range by a rheostat.

20 By the method disclosed in my invention, however, these difficulties are avoided as the operator is merely required to change from one lamp to another by swinging the pivotally mounted bracket for major changes in light intensity, and the operator may use a rheostat for minor changes in light intensity. Thus much unnecessary heat is avoided, the light can be more accurately controlled, and 25 much less current is consumed.

30 Having thus described my invention, what I claim as new and desire to secure by Letters Patent is:

1. In a photographic printing machine the 35 combination with a printing panel, of a source of light for said printing panel comprising a plurality of lamps and a pivotal base supporting said lamps.

40 2. In a photographic printing machine the combination with a printing panel, of an adjustable source of light for said printing panel comprising a plurality of lamps, each lamp having a different intensity and a pivotally mounted bracket supporting said lamps.

45 3. In a photographic printing machine, the combination with a printing panel, of an adjustable source of light for said panel comprising a plurality of lamps, each lamp having a different intensity, an insulating block carrying a plurality of contact points, and a pivotally mounted bracket supporting said lamps and insulating block.

50 4. In a photographic printing machine the combination with a printing panel, of an adjustable source of light for said panel comprising a plurality of lamps of different intensities, an insulating block carrying a plurality of contact points, each point connected to the corresponding lamp socket, a spring contact to complete any one of the plurality of lamp circuits, and a pivotally mounted bracket supporting said lamps and insulating block.

55 5. In a photographic printing machine the

combination with a printing panel, of an adjustable source of light for said panel comprising a plurality of lamps of different intensities, an insulating block of fibrous material carrying a plurality of contact points, 70 each point connected to the corresponding lamp socket, a spring contact, completing any one of the plurality of lamp circuits, mounted on an insulated base, a pivotal bracket supporting said lamps and insulating contact point block and a pivot supporting said bracket and insulated spring contact base. 75

6. In a photographic printing machine of the type utilizing a concentrated light source, 80 the combination with a printing panel of a pivotally mounted lamp bracket supporting a plurality of concentrated filament lamps, each lamp having a different intensity, a pivotal support for said bracket, an insulating block supporting a series of contact points carried by the bracket, each contact point being connected to a lamp, and means to simultaneously bring one point at a time into operative position with a spring contact, and the corresponding lamp into operative position for illuminating the printing panel, said spring contact being adapted to hold the bracket in said position. 85

7. In a photographic printing machine the 90 combination with a printing panel a source of light for said printing panel comprising a plurality of adjustable lamp sockets and pivotal base supporting said lamps.

8. In a photographic printing machine the 100 combination with a printing panel, an adjustable source of light for said printing panel comprising a plurality of lamps, each lamp having a different intensity, a plurality of radially adjustable lamp sockets supporting 105 said lamps, and a pivotal bracket supporting said bracket.

9. In a photographic printing machine the 110 combination with a printing panel of an adjustable source of light for said panel comprising a plurality of lamps, each lamp having a different intensity, a plurality of radially adjustable lamp sockets supporting said lamps, an insulating block carrying a plurality of contact points, and a pivotal bracket supporting said bracket and insulating block. 115

10. In a photographic printing machine the combination with a printing panel, of an 120 adjustable source of light for said panel comprising a plurality of lamps of different intensities, a plurality of radially adjustable lamp sockets supporting said lamps, a plurality of thumb screws controlling the adjustment of 125 said lamp sockets, an insulating block carrying a plurality of contact points, each point connected to the corresponding lamp socket, a spring contact to complete any one of the plurality of lamp circuits, and a pivotal 130

bracket supporting said lamps and insulating block.

11. In a photographic printing machine of the type utilizing a concentrated light source, the combination with a printing panel of a pivotally mounted lamp bracket supporting a plurality of radially adjustable lamp sockets carrying a plurality of concentrated filament lamps, each lamp having a different intensity, a pivotal support for said bracket, a series of thumb screws carried by the bracket, each screw controlling the adjustment of the corresponding socket to its relation thereto, an insulating block supporting a series of contact points carried by the bracket, each contact point connected to a lamp socket and means to simultaneously bring one point at a time into operative position with a spring contact and its corresponding lamp into operative position for illuminating the printing panel, said spring contact being adapted to hold the bracket in said position.

12. In a photographic printing machine the combination with a printing panel, of a source of light for said panel including a movably mounted lamp bracket, a plurality of lamps carried thereby, a plurality of incomplete circuits including the lamps, and means tending to retain the bracket in a set position, said means also forming a switch for completing an incomplete circuit to a lamp.

13. In a photographic printing machine the combination with a printing panel, of a source of light for said panel including a movably mounted lamp bracket, a plurality of lamps carried thereby, a plurality of incomplete circuits including the lamps, and a spring arm adapted to resiliently engage said bracket for locating the bracket and completing one lamp circuit.

14. In a photographic printing machine the combination with a printing panel, of a source of light for said panel including a movably mounted lamp bracket, a plurality of lamps carried thereby, a plurality of incomplete circuits including the lamps and means for completing one circuit at a time including a pair of cooperating contacts, one adapted to enter into the other, said contacts serving as a snap latch tending to hold the bracket in a set position.

Signed at Rochester, New York, this 16th day of October, 1929.

ROY S. HOPKINS.
